ELECTRIC SWITCH

William E. Brown, Auderson, Ind., assignor to General Motors Corporation, Detroit, Mich., a corporation of Delaware

Application October 15, 1952, Serial No. 314,930

6 Claims. (Cl. 200—61.78)

This invention relates to improvements in electric switches and more particularly to switches of the plunger type adapted to be operated by the closure of a door. Switches of this type generally embody a housing or body having a chamber which houses the movable contact and one end of a stationary contact or a terminal which is adapted for engagement with the movable contact in the normal position of the switch.

An object of the present invention is to provide for a plunger type switch with a stationary contact of novel form.

Another object of the invention is the provision of an efficient switch mechanism, parts of which are simple and inexpensive and capable of being assembled together entirely by hand.

Another object of the invention is to provide a body and a contact member which are so constructed as to materially facilitate assembly of the contact member with the body in a correct and rigid manner and to provide a contact member which may be economically produced from sheet metal.

Another object of the invention is to provide a detachable one-piece sheet metal contact member which is so constructed so as to provide a base-portion to close one end of the chamber of the housing, to provide a contact portion engageable with a movable contact within the chamber of the housing, to provide a receptacle outside the chamber for the reception of a terminal; and to provide flexible portions cooperating with openings and abutments provided by the housing for retaining the contact and housing in assembled relation.

Further objects and advantages of the present invention will be apparent from the following description reference being had to the accompanying drawings wherein a preferred embodiment of the present invention is clearly shown.

In the drawing:

Fig. 1 is a side view of a switch constructed in accordance with this invention.

Fig. 2 is a top view thereof.

Fig. 3 is a bottom view thereof.

Fig. 4 is a longitudinal sectional view through the switch on line 4—4 of Fig. 2.

Fig. 5 is a longitudinal sectional view taken on line 5—5 of Fig. 1.

Fig. 6 is a plan view of an insulator embodied in the switch structure.

Fig. 7 is a perspective view of the stationary contact element of the switch.

Fig. 8 is a top plan view of the switch housing.

Fig. 9 is a bottom plan view of the switch housing.

Fig. 10 is a fragmentary sectional view illustrating the opened position of the switch.

Referring to the drawings, 20 designates a switch assembly which is adapted for assembly in a support 21 for operation by a closure member 22. The switch assembly 20 comprises a body or housing 23 of molded insulating material or plastic. As viewed in Fig. 3 the

2

right end 24 of the body is circular in cross section, and its left end 25 is substantially oblong or rectangular in cross section, see Fig. 8. The housing has arcuate end walls 26 and flat side walls 27. With this formation 5 the right end portion 24 overhangs the left end portion 25 of the body to provide flanges or abutments 28, the purpose of which will be described hereinafter.

Referring to Fig. 9 the right end portion 24 of the body is formed with a transverse slot 30 to form spaced 10 guide surfaces 31 and a ledge 32. The enlarged end 24 has space openings extending completely through the flanges 28 as illustrated in Fig. 4. The body 23 is formed with a cavity or chamber 34 extending from the ledge 32 and terminating short of the other end 25 of the body to provide an end wall 35 provided with an opening 36. The cavity consists of a cylindrical wall 37 interrupted by a lateral groove 38. The end wall is formed with a pocket 39 which is a reduced extension of the groove so as to provide a shoulder 40.

20 The cavity 34 receives an operating member or plunger 45 of insulating material or plastic and includes a stem 46 and a head 47 carrying a movable contact 48. The stem 46 is slidable into and out of an annular bearing flange 49 of a plate 50 which is attached to the body by 25 riveting over the flange 49 as at 51 against the inner surface of the end wall to hold the plate 50, a fastening member 52, and the body 23 in assembled relation.

The fastening member 52 comprises a U-shaped member having a yoke 53 formed with an opening having 30 diametrically opposite recesses to receive lugs 54 extending from the end wall 35 so as to prevent the fastening member from turning relative to the body. The side edges of the arms 55 of the member 52 are formed with teeth 56 which are adapted to bite into a metal support 35 to provide a ground connection for the switch.

The plunger 45 is assembled within the body 23 by inserting same at the mouth of the chamber or cavity 34 with the stem 46 passing through the bearing flange 49. The contact 48 has a sliding fit with the cylindrical wall 40 portion of the chamber or cavity 34 to guide the plunger 46 in straight line axial movements with respect to the body 23. The contact 48 is capable of engaging riveted over end 51 of the flange 49 to limit the outward movement of the plunger and also to complete a circuit through 45 the switch. The plunger 45 carrying the contact 48 is projected to the left as viewed in Figs. 4 and 5 by an operating spring 59 disposed between an insulating plate 60 and the contact 48. The plate 60 rests on the ledge 32 to insulate the contact member 65 from the spring so 50 as to prevent current passing through the spring. The plate 60 has cut outs 61 diametrically opposed and dimensioned to be received within the transverse slot 30 one of the notches receives a lug 62 formed on the ledge 32 while the other will straddle a resilient contact arm 71 of a stationary contact member 65 shown in 55 Fig. 7.

The stationary contact member 65 consists of the base portion 66 having a spherical portion or dimple 67. The base 66 has integral side arms 68 provided with integral spring fingers 69 which are bent outwardly from the normal plane of the arms 68 as shown in Fig. 7. The base 66 is also provided with resilient end arms 70 and 71. The arm 70 is bent back over the base as illustrated to form a receptacle for the reception of a spade terminal 72. The extreme end of the arm is flared outwardly at 73 to facilitate insertion of the spade terminal 72 into the receptacle. The space between the base and the arm is less than the thickness of the spade terminal and the tension of the arm is such as to cause it to force the spade terminal against the base so that a good electrical connection is had between the members. 70

Arm 71 is bent at an acute angle relative to the base

66 so that it will flex outwardly when engaged by the movable contact 48. The arm 71 is formed with a contact portion 74 engageable with the movable contact 48 when the plunger 45 is in its normal position as shown in Fig. 5. The extreme end 75 of the arm 71, when the contact 65 is assembled with the body 23 extends into the pocket 39. When the switch is in its normal position the movable contact 48 carried by the plunger causes outward flexing of the free end of the arm which effects good electrical contact engagement between the contact portion 74 and the contact 48, and provides a wiping action therebetween to keep the contact surfaces free of corrosion.

It will be understood that the contact member 65 can be inserted axially from the bottom or enlarged end 24 when the arms 68 are aligned with respective openings 33. As the contact member is moved toward the housing or body 23 the fingers 69 engage walls 80 of the openings causing the fingers to be bent inwardly against their resistance while they are within the confines of the openings. When the edges of the fingers pass the inner face of the abutments the fingers spring outwardly and overlie the abutments to lock the contact member in non-retractile supported position.

As shown in Fig. 4 it is preferred to chamfer the inner walls of the openings, as at 81, to facilitate the insertion of the arms 68, this is not essential as the angular disposition and resilience of the arm may be such that they can be forced easily through the openings.

One of the advantages of the present construction of the body and the other switch parts described, is that the plunger 45, spring 59, plate 60 and the stationary contact 65 can be assembled with the body without the use of screws, bolts or the like. The stationary contact member 65, can be detached as required by simply flexing the resilient fingers 69 inwardly by a suitable tool until they are free of the flanges and applying force to the base the contact member can be removed from the body.

It will be clear without detailed explanation that the spring 59 will exert a force on the plunger 45 to hold the contact in engagement with the flange 49 as shown in Figs. 4 and 5. When the plunger 45 is forced inwardly against the force of the spring 59 the contact engagement between the contact and contact portion will be interrupted, as shown in Fig. 10 and the contact portion 74 in this position cannot touch the flange 49 due to the fact the free end 75 engages the shoulder 40 to limit the inward movement of the arm.

While the embodiment of the present invention as herein disclosed, constitutes a preferred form, it is to be understood that other forms might be adopted.

What is claimed is as follows:

1. In an electric switch having a non-conducting body having a chamber extending longitudinally thereof and opening at one end of the body; exterior side flanges adjacent the open end of the chamber carried by the body, each of said flanges having an opening; and a one piece detachable conducting means for closing said open end of said chamber, said means including a base for closing the chamber and having a flexible contact extending into the chamber and having a pair of spaced arms, said arms comprising flexible tangs cut into the arms on the diagonal thereof, said arms being forcibly inserted in the respective openings to permit the tangs to return to the normal state and overlie the flanges for fixedly holding the conducting means to the body, and for preventing accidental removal of the conducting means from the body.

2. In an electric switch having a one-piece molded insulating body having a chamber formed therein and opening to one end thereof, said body having diametrically opposite side exterior flanges formed adjacent the opened end of the chamber, each flange having an aperture therethrough; an actuator movable in said chamber; a movable

contact controlled by the actuator; and a detachable one-piece conducting member carried by the body, said contact member having a base for closing the open end of the chamber, a contact portion engageable with the movable contact in the normal position of the actuator and having spaced arms, each arm being severed at a plurality of places and bent in opposite directions from the plane of their respective arms to provide locking tangs to overlie the flanges, said tangs being yieldably urged toward each other when forced through their respective openings until the tangs pass through the openings whereby the tangs return to their normal state, said tangs cooperating with the flanges to prevent accidental removal of member from the body.

3. In an electric switch, the assembly comprising a one-piece body of insulating material having a chamber extending from one end terminating short of the other end to provide an end wall having an aperture therein, said one end having diametrically opposite side flange provided with through openings therein; a plunger having a shank extending through said aperture; a movable contact controlled by the plunger; a detachable unitary contact member includes a base for closing one end of the chamber, an integrally connected receptacle for a spade terminal, an integrally connected contact portion engageable with the movable contact in its normal position, and a pair of arms, each arm having a cut-out portion bent out of the plane thereof to provide a locking tang, said arms being forcibly inserted in the respective openings with the tangs cooperating with the flanges for fixedly holding the contact member to the body.

4. In an electric switch, the assembly comprising, a non-conducting body having a chamber extending longitudinally thereof and a pair of spaced openings, said openings positioned at opposite sides of the chamber, said body having a lateral abutment adjacent each opening; a detachable conducting member including a base for closing one end of the chamber, a terminal receiving receptacle on the side of the base; a contact portion on the other side of the base and extending into said chamber and a pair of arms formed integrally on said other side of said base, said arms having flexible cut out portions and being forcibly insertable into said openings so that the flexible portions thereof will engage the abutments for fixedly holding the conducting member to the body.

5. In an electric switch, the assembly comprising a one-piece non-conducting body having a chamber extending from one end and terminating short of the other end to provide an end wall provided with an aperture, said body being enlarged at said one end to provide diametrically opposite side abutments provided with through openings; a plunger reciprocally movable through said aperture; a movable contact located within the chamber and controlled by the plunger upon movement thereof; and a detachable contact member including a base for closing said one end of the chamber, a terminal receiving receptacle carried on one side of the base, a contact portion carried by the base on the other side thereof and engageable with the movable contact in its normal position, and arms also on said other side, said arms having cut-out flexible portions, said arms forcibly inserted in said openings so that the flexed portion will engage the abutments for fixedly holding the conducting member to the body.

6. As an article of manufacture, a detachable closure for a switch housing, said closure comprising a one-piece spring metal member having a base portion folded upon itself in one direction to provide a spring clip adapted to receive a terminal and having a contact arm extending from one end of the base and bent in the opposite direction from the base to engage a movable contact within the housing; and an ear extending from each side edge of the base and bent in said opposite direction, said ears adapted to pass into respective openings provided

by the housing, the material of each ear being severed at a plurality of places and bent from the plane of their respective ears to provide locking tangs, said tangs being yieldably urged toward each other when forced through the respective openings and when the tangs pass through the opening the tangs return to their normal state and overlie abutments adjacent the opening to detachably hold the closure to the housing.
